(57) **CLAIM**

The ornamental design for a tool handle clamp, substantially as shown and described.

DESCRIPTION

FIG. 1 is a front, right side and top perspective view of a tool handle clamp comprising a new, original and ornamental design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front, right side and top perspective view thereof shown in an environment use; and,

FIG. 9 is a front, right side and top perspective view thereof shown in an environment use.

The broken lines depict environmental structure and form no part of the claimed design.
